LOCK CONSTRUCTION

Adam Schoorel, New York, N. Y., assignor to
 Francis Keil & Son, Inc., a corporation of New
 York

Application January 31, 1934, Serial No. 709,127

58 Claims. (Cl. 70—14)

This invention relates to lock construction and particularly to a construction for preventing unlocking of the lock after certain mechanism of the latter has been tampered with.

5 One of the objects of the invention is to provide a lock construction achieving a high factor of safety without complicating structural and manufacturing facility and more particularly to provide a lock construction of this character in 10 which actuation of the mechanism in which bolt-withdrawing direction is dependably precluded even though the key-controlled mechanism has been broken away or otherwise removed. Another object is to provide a lock construction of 15 the above-mentioned character which will be of simple and thoroughly practical construction capable of reliability of action, rugged in construction, and dependably tamper-proof. Another object is to provide a lock construction in 20 which such objects as the above are achieved in a thoroughly practical manner and yet having its parts so arranged that ease and speed of assembly are dependably achieved. Another object is to provide a lock construction having such tamper-proof characteristics as above-mentioned 25 but in which restoration of the construction for normal operation will be quickly and easily achieved. Other objects will be in part obvious or in part pointed out hereinafter.

30 The invention accordingly consists in the features of construction, combinations of elements, and arrangements of parts as will be exemplified in the structure to be hereinafter described, and the scope of the application of which will be indicated in the following claims.

In the accompanying drawings in which are shown several of the various possible embodiments of certain features of my invention,

Figure 1 is a vertical sectional view through a 40 door or the like and through the related lock and key-controlled mechanisms;

Figure 2 is a vertical sectional view as seen along the line 2—2 of Figure 1, showing in plan the internal mechanism;

45 Figure 3 is a vertical sectional view, as seen along the line 3—3 of Figure 2;

Figure 4 is a plan view of the closure or rear plate of the casing of the lock mechanism;

50 Figure 5 is a view of the right-hand portion of the apparatus, as seen in Figure 2, but with certain parts thereof in changed position;

55 Figure 6 is a plan view of another embodiment of certain features of my invention, as seen from the rear and open end of the lock casing, the bolt

mechanism being shown in bolt-withdrawn position;

Figure 7 is a view similar to that of Figure 6, but it shows the mechanism in bolt-projected position;

Figure 8 is a vertical sectional view as seen along the line 8—8 of Figure 7;

Figure 9 is a view similar to that of Figure 7 but shown only in part or fragmentarily showing the relation of certain parts of the mechanism after 10 certain other mechanism has been tampered with;

Figure 10 is a vertical transverse sectional view showing the manual control;

Figure 11 is a vertical sectional view on line 15 11—11 of Figure 6;

Figure 12 is a plan view of the back or closure plate of the lock mechanism of Figures 6—11 inclusive;

Figure 13 is a plan view as seen from the rear, 20 with the cover removed, of another form of lock mechanism, with the parts in bolt-withdrawn position;

Figure 14 is a view similar to that of Figure 13, but showing the parts in bolt-projected position;

Figure 15 is a vertical sectional view through the lock mechanism of Figures 13 and 14 and through the door or like part with which the lock may be associated;

Figure 16 is a plan view of the rear or closure 30 plate of the lock mechanism of Figures 13—15;

Figure 17 is a perspective view on an enlarged scale of one of the parts employed in the lock mechanism of Figures 13—15;

Figure 18 is a perspective view of an assembly 35 plate of that lock construction;

Figure 19 is a detached perspective view of one of the parts used in the mechanism of Figures 13—15, and

Figure 20 is a perspective view of another part 40 of the lock mechanism of Figures 13—15.

Similar reference characters refer to similar parts throughout the several views of the drawings.

Considering first the lock construction shown in Figures 1—5, it is first to be noted that it includes a casing 20 shaped substantially as shown in the drawings whose side and end walls and front wall 20^a are preferably integrally formed 50 and which may be closed by a back plate 21 (Figure 4), the casing being provided with suitable holes 22 (Figure 2) and the back plate 21 with suitable cutouts 23 which register with the holes 22 for the reception of suitable screws (not 55

shown) for securing the casing to a door 24 (Figure 1) or the like.

Within the casing 20 is carried what I shall term a slide 25, the latter being conveniently in the form of a casting and being of substantial thickness and weight in order to lend adequate strength; at its left-hand end, as seen in Figure 2, the slide 25 is shaped to provide two arms 26-27 carrying at their ends plunger-like bolt members 28-29, respectively, preferably aligned with each other and movable, with the member 25, transversely of the casing 20 and hence in a direction up and down as viewed in Figure 2.

The bolt members 28-29 are adapted to coact with and to enter the eye members 30 and 31, respectively, of a keeper structure 32 secured to the door frame or casing, the casing 20 extending beyond the edge of the door and thus overlapping the door frame and being provided with suitable apertures to permit the eye-like keeper portions 30-31 to enter into the casing 20. If, then, the slide 25 is moved upwardly, as viewed in Figure 2, and into the position shown in that figure, the bolt members 28-29 enter the eye members 30 and 31, respectively, and thus lock the door to the door frame.

The slide 25 is limited in its bolt-projecting movement by a projection 25^a (Figure 2) thereon which rides into engagement with the side wall of the casing while its movement in bolt-withdrawing direction (downwardly in Figure 2) is limited by the engagement of portions 25^b thereof with the opposite side wall of casing 20. Slide 25 is guided in this transverse movement relative to the casing 20 by guideways 32^a (Figures 2 and 3) suitably formed in both the slide 25 and the front wall 20^a of the casing, and coacting with these guideways 32^a is a lug 25^c (Figures 2 and 3) projecting from the slide 25 and engageable in a transversely extending slot 21^a (Figure 4) in the back or cover plate 21, the thickness of the slide 25 being, moreover, as better appears in Figure 3, such that the spaced walls 20^a-21 receive the member 25 therebetween for easy guiding movement in the directions above described. The mounting or securing in place of the closure plate 21 will be described later.

For actuation of the slide 25 and hence of the bolt members 28-29 in the direction above described, there are provided two actuating members 33 and 34 (Figure 1); member 33 is in the form of a double armed crank having two arms 33^a and 33^b and it is carried on the inner end of a sleeve 35 (Figure 1) of a handle or knob 36, sleeve 35 extending through the front wall 20^a for free rotation therein. The arms 33^a-33^b are shaped substantially as shown in Figure 1, being thereby engaged by the free end 37^a of a spring 37 whose helical portion extends about a stud 38 (Figures 1 and 2) and whose other end 37^b (Figure 2) rests against the end wall of the casing 20. Double crank 33 may therefore be manually rotated by the handle 36 for control of the lock mechanism from the inside of the door, spring 37 acting upon the arms thereof yieldingly and causing the crank arm and knob always to be returned to a position such as is shown in Figure 2.

Member 34 is in the form of a simple crank arm and is fixed to a bushing 39 (Figures 1 and 4) that is rotatably carried by the back plate 21 in axial alignment with the sleeve and knob 35-36. Bushing 39 has a transverse slot 40 at its outermost face (Figures 1 and 4) for the reception of the actuating bar 41, rectangular in cross-section, of the key-controlled mechanism generally

indicated at 42, the latter being mounted in a suitable hole 24^a in the door 24 and secured thereto as by the plate 42^c (Figure 1) and screws 43, in a manner well known. The mechanism 42 is provided with any suitable tumblers, wafers, or the like, to be controlled by the key 44. Accordingly, upon the insertion of the proper key 44 from the outside of the door 24, the tumbler or like mechanism is set to permit rotation of the actuating bar 41 by the key 44 whereupon the single crank 34 may be rotated.

The sleeve 25 (Figure 1) is, as above noted, hollow so that the bar 41 may freely extend entirely through the lock casing and into the sleeve 25, thus making it unnecessary to have to cut off or fit the length of the operating bar 41 where the latter might otherwise be too long.

Considering now the actuation of the slide 25 with its bolts in response to the actuation of either of the cranks, it is first to be noted that the right-hand end (Figure 2) of the slide 25 is provided with extensions 25^d and 25^e having end faces inclined toward each other, but these extensions are spaced apart to slidably receive therebetween the block-like head 45 of a plunger 46 slidably received in a cylindrical channel 25^f in the slide 25 (see Figure 2). Between the inner end of plunger 46 and the bottom of the hole on channel 25^f is interposed a spring 47 which pushes the plunger 46 and hence the head 45 to the right, that action being limited by a screw 48 threaded into the side of the plunger 46 and whose head slides along the slot 25^g in the slide 25.

As better seen in Figure 3, the head 45 projects beyond the slide 25 and virtually contacts the inner face of the closure plate 21. The latter carries a block or lug 49 (Figures 3 and 4) positioned in what would, except for the movements herein-after described, be the line of movement of the head 45 as it is carried transversely of the casing 20 with the slide 25.

With the parts in the position shown in Figure 2 (bolts projected), the head 45 engages at one side of the lug 49 and in the view shown in Figure 3 the head 45 will be seen to be abutting against the upper edge or side of the lug 49. This action precludes the slide 45 and hence the bolts from partaking of a movement in bolt-withdrawing direction (downwardly in Figure 2), lug 49 dependably blocking such movement.

However, should either of the cranks 33 or 34 be rotated, the crank arm swings in counter-clockwise direction as viewed in Figure 2, past the inclined end face of extension 25^d and into engagement with the end face of the head 45 but continued rotary movement of the crank arm pushes the head 45 and the plunger 46 to the left, thus displacing the head 45 from its abutting position with respect to the lug 49 (moving it to the right of lug 49 as viewed in Figure 4), whereupon continued rotation of the crank arm to complete a 180° rotation thereof forces the slide 25 downwardly (as viewed in Figure 2) concluding the withdrawal of bolts 28-29 from the keeper, and as the slide 25 reaches the opposite end wall of the casing so that the crank arm begins to move out of the space between the extensions 25^d and 25^e, the spring 47 pushes the plunger 46 and head 45 to the right and upon the conclusion of these movements, the head 45 finds itself transposed to the opposite side or edge of the lug 49 (Figures 3 and 4) of the cover plate 21, thus bringing about an abutting relation which now precludes unintentional movement of the slide 25 in bolt-projecting direction.

A frequent mode employed by burglars and the like of gaining access to a locked door is, referring now to Figure 1, to cut or break away or otherwise remove the key-controlled mechanism 42 and to withdraw with it the operating bar 41, thus exposing through the hole 24^a in the door 24 or through the hole 42^a in the securing plate 42 the transverse slot 49 (Figures 1 and 4) in the bushing 39 which controls the rotation of the 10 crank arm 34; with that slot exposed, the insertion of a screw driver or like implement therein rotates the crank 34 and thus actuates the lock mechanism to withdraw the bolts, whereupon it will be seen that access has been very easily and 15 simply gained.

Aside from certain unique features already above described, my invention contemplates the achievement of a thoroughly practical and reliable means for precluding the attainment of 20 unauthorized access in a manner like that just described and accordingly I provide in the casing 20 (Figure 2) a stud or post 50 preferably integrally cast or formed with the casing 20, the post 50 extending at right angles to the front 25 wall 20^a; pivoted on this stud is a member 51 having two arms 51^a and 51^b, member 51 being biased to swing in clockwise direction by a spring 52 whose helical portion extends about the stud 50 whose one end rests against the side wall of 30 casing 20 and whose other end rests against a projection 51^c of the member 51, as is well shown in Figure 2.

The arm 51^b of the member 51, shaped as indicated in Figure 2, bears against the inwardly projecting portion of the operating bar 41, as appears clearly from Figures 1 and 2, spring 52 tending always to hold the member 51 against the operating bar 41 even during the rotation of the latter and being of sufficient strength to move it past 40 the position shown in Figure 2 assuming that the operating bar 41 is removed.

The other arm 51^a extends in the space between the extension 25^d and an extension 25^e which carries the motion-limiting projection 25^a (Figure 2), 45 the side face of extension 25^d being slotted as at 25^j, if necessary, to better accommodate the arm 51^a.

The right-hand ends of the extensions 25^d and 25^e, as viewed in Figure 2, are slotted, the slot being of sufficient thickness to receive the plate-like arm 51^b of the member 51 if the latter were swung in clockwise direction, as viewed in Figure 2, while the side face of extension 25^e of the slide 25 (Figure 2) carries a latch member 53 which conveniently is in the form of a leaf spring, hook-shaped at its right-hand end and suitably secured, preferably in a slot in the side of the member 25, as by a screw 54. The extreme lower end of the arm 51^b is shaped as indicated at 51^d (Figure 2), 60 having an under face that is cam shaped or suitably curved to cause the hook-shaped end of the spring 53 to yield and having an opposed surface with which and over which the hook-shaped end of the spring 53 may engage.

Assuming now that the lock mechanism is in bolt-projected position (with all of the parts in the position as shown in Figure 2) and assuming now that the operating bar 41 is withdrawn for example in a manner like that above described, bar 41 (Figures 1 and 2) no longer is in position to hold the member 51 in the position shown in Figures 1 and 2 and hence spring 52 is now free to snap or spring or move the member 51 in clockwise direction. This movement results in the arm 51^a entering the slots

in the ends of the extensions 25^d and 25^e and in the yieldable latch member 53 being snapped over the locking portion 51^d (see now Figure 3), latch 53 thus securely holding the member 51 against movement in counter-clockwise direction.

In that position, the arm 51^a of member 51 engages against the inner face of the extension 25^e (see Figure 5) and hence, with the member 51 locked against swinging movement by the latch 53 and being carried by the stud 50 of the casing 20, the extension 25^e (Figures 2 and 5) and hence the slide 25 is blocked, independently of the plunger head 45, against movement, (downwardly as viewed in Figures 5 and 2) in 15 bolt-withdrawing direction. Or viewed in a different light, the arm 51^a in the position shown in Figure 3 forms a relatively fixed abutment and between it and the side wall of the casing 20 is held the extension 25^e of the slide 25, the latter 20 being thus held against movement.

The plunger head 45 is also slotted to accommodate the arm 51^b of the member 51, the slots 25^s, 45^s and 25^s in the members 25^d, 45 and 25^e (see Figures 3 and 2) being in alignment for the 25 reception of the arm 51^b. The arm 51^b, therefore, does not, in its clockwise movement from the position of Figure 2 to the position of Figure 3, move the plunger head 45 to the left, so that the plunger head 45 remains in abutting 30 relation to the lug 49 (Figures 5 and 4) on the closure plate 21.

It is particularly to be noted that by the withdrawal of the operating member 41, the arm 51^b of the member 51 is, in the manner above described, swung to the left of the axis of the bushing 39 (Figure 1) as these parts are viewed in Figures 2 and 5; that is, the arm 51^b is held to the right of operating bar 41 by the latter so long as the latter remains inserted but when 40 it is once withdrawn, arm 51^b swings over to the left (see now the position in Figure 5) so that if a screw driver, bar, or other implement is now inserted through the slot 49 in bushing 39 in the endeavor to effect operation of the lock 45 mechanism in bolt-withdrawing direction, arm 51^b is now to the left of such implement.

Assume then, that such implement has been inserted and its rotation commenced so as to swing the crank arm 34; crank 34 swings (see 50 Figures 2 or 5) past the inclined edge of the extension 25^d and into engagement with the plunger head 45, moves the plunger head 45 out of engagement with the lug 49 (Figures 4 and 5) and continued rotation of the arm 34 commences a downward movement of the slide 25; but such downward movement of the slide 25 55 operates upon the arm 51^a (Figure 2) of the member 51 and starts swinging the latter in counter-clockwise direction, disengaging its portion 51^d from the spring latch 53, but now continued counter-clockwise swinging of the member 51 is precluded by the inserted implement itself against which the arm 51^b is thus made to abut. It will be noted that now continued movement 60 of the slide 25 is precluded for such movement cannot be carried on without continued counter-clockwise swinging of member 51 and such swinging is positively blocked by the inserted instrument itself. Thus, such tampering and such attempted unlocking of the lock mechanism are 65 fruitless.

Should the thus inserted and now ineffective implement be withdrawn, spring 52 rotates the member 51 in clockwise direction (as viewed in 70 75

Figure 2) and such rotation reverses the partial movement of which the slide 25 had partaken, spring 47 snapping the plunger head 45 back into abutting relation with respect to the lug 49 while latch portion 51^d of member 51 reengages the spring latch 53, thus restoring the parts to their normal or intended relation.

However, crank arm 33^a (Figures 2 and 1) operated by the handle or knob 36 and hence 10 operable from the inside of the door can be operated to move the slide 25 down in bolt-withdrawing direction, so that the lock mechanism may still be operated from the inside even though it has been tampered with as above typified. 15 Moreover, this facility for operation from the inside is utilized when a new key-controlled mechanism 42 and a new operating bar 41 are put in place of the one that had been removed and makes for speed of restoration of the lock mechanism in its entirety.

Thus, in reinserting a new operating bar 41, the handle or knob 36 is rotated to move the slide 25 in bolt-withdrawing direction, such movement, as will now be clear, swinging the member 51 in counter clockwise direction, as viewed in Figures 2 or 3, and that movement is continued until the arm 51^b has been moved to the right (as viewed in Figure 2 or 3) of the axis of the bushing 39 or bar-receiving slot 40, whereupon the new bar 41 is inserted through the slot 40 and, when the knob 36 is released and normal operation resumed, the new operating bar 41 is in the path of clockwise rotation of arm 51^b and thus the parts are in readiness for a repetition of the safeguarding action, 35 when need therefor arises, all as above briefly outlined.

The post 50 about which the member 51 is pivoted has a threaded hole for the reception of a screw 55, the screw 55 passing through a hole 56 40 (Figure 4) in the closure plate 21 and thus securing the latter with respect to the casing 20, suitable lugs 57 (Figure 3) being appropriately distributed throughout the periphery of the side walls of the casing 20 to properly support the closure 45 plate 21, in coaction with the post 20, in spaced relation (see Figure 3) from the front wall 20^a.

Referring now to Figures 6-12 inclusive, I have there shown certain features of my invention in connection with and coacting with a different kind 50 of bolt construction and bolt-operating mechanism. Referring first to Figures 6 and 7, there is a lock casing 60 having an end wall 60^a provided with two apertures 60^b and 60^c, the apertures being generally circular so as to slidably support 55 the rotatable bolts 61 and 62, respectively, but having portions cut out to receive the projections 61^a and 62^a of the bolts, the bolts being at their ends substantially T-shaped due to the provision of two of such projections one on each side. The 60 keeper (not shown) is provided with similarly shaped bolt-receiving holes or apertures through which the T-shaped heads are first projected and relative to which the bolts are then rotated so as to prevent withdrawal of the bolts from the keeper.

The right-hand ends 61^b and 62^b of the bolts are rotatably supported in a front flange 63 of a main sliding plate 64 which is slidably supported and guided in ways 65 and 66 (Figures 7 and 8) for movement in the direction of the axes of the 70 rotatable bolts 61-62; the connection between the bolts and the flange or wall 63 of the sliding plate 64 is such that, though rotation of the bolts relative to the sliding plate 64 may freely take place, relative movement in the direction of the axes of the bolts cannot take place so that the bolts must 75

partake of whatever sliding movement that the sliding plate 64 partakes of.

One of the bolts, such as bolt 61, carries a lug 61^c (Figure 6) whose under face, as viewed in Figure 6, bears against the upper face of a lug or 5 projection 60^d integrally formed with and within the casing 60, so that movement of the bolt 61 toward the left, as viewed in Figure 6, cannot be accompanied by rotation of the bolt until the arm 61^c has passed over the lug 60^d, whereupon 10 rotation of the bolt 61 may take place, arm 61^c swinging down into the space between the lug 60^d and the front wall 60^a and hence into the position shown in Figure 7.

On their adjacent side portions, bolts 61-62 15 are provided with so-called spiral but in reality helical slots 61^d and 62^d and resting in these helical slots is a cross-bar 67 which is carried at the left-hand end of an arm 68 which passes through a suitable hole in the wall or flange 63 of the main 20 sliding plate 64 and which is secured to or forms a part of an auxiliary sliding plate 69 which rests against the main slide 64 and is guided thereby, main slide 64 having side flanges 64^a and 64^b (Figure 8) between which the auxiliary slide 69 fits 25 and by which it is guided in its sliding movement relative to the main slide 64.

Auxiliary slide 69 is provided with a transverse guideway 70 extending transversely thereof, being milled or cast therein (Figures 6, 7 and 10) for 30 slidably receiving a detent member 71 shaped in longitudinal cross-section, as is better shown in Figure 10 and in elevation as appears in Figures 6 and 7. While auxiliary slide 69 may move relative to the main slide 64 in the direction of the 35 axes of the bolt 61-62, the detent member 71 may partake of sliding movement in a direction transversely of the axis of the bolts.

The detent member 71 has a connection, to be presently described, with a crank member 72 (see 40 Figure 10) which is mounted on the inner end of a hollow sleeve 73 rotatably mounted in the outer wall 60^e of the casing 60 and terminating in a handle or knob 74 whereby, the lock being mounted upon the inside face of the door, the lock mechanism may be manually actuated from within.

As better appears in Figure 10, the ways 65-66 space the main slide 64 sufficiently from the wall 60^e of the casing as to allow ample space for the rotational movements given the crank arm 72; 50 the latter, moreover, carries at its outer end a crank pin 75 which extends through a slot 76 in the main slide 64, through a slot 77 in the auxiliary slide 69 and through a hole 78 in the detent member 71; moreover, the crank pin 75 55 extends also through a hole in a plate-like lever or member 79 (see also Figures 6 and 7) which will be more clearly hereinlater described, and threaded into the crank pin 75 is a screw 80 which thus holds all of the parts through which 60 the crank pin 75 passes in assembled relation with respect to each other as well as with respect to the casing 60.

The slot 77 in the auxiliary slide 69 extends transversely of the axis of the bolts 61-62 and 65 is of a uniform width to snugly receive the crank pin 75, thus causing the auxiliary slide 64 to partake of movement of translation in the direction of the bolt axis whenever the crank 70 72 is rotated by the handle 74. The slot 76 in the main slide 64, however, is shaped somewhat as is indicated in Figure 9 whereby, as will more clearly appear later, the main slide 64 and the crank pin 75 may partake of relative movement in the direction of the bolt axis. 75

Auxiliary slide 69 carries a stud 81 (Figure 6) about which extends a wire spring 82 whose one end bears in a recess in the end face (the upper end as viewed in the drawings) of the detent member 71, as is better shown in Figure 10, thus biasing the member 71 downwardly as viewed in the drawings and similarly biasing the crank arm 72.

The plate-like member 79, freely pivoting about the screw 80 (Figures 6, 8 and 10) has secured thereto a leaf spring 83 whose unanchored end extends into a slot 71^a (Figures 8 and 10) formed at one end of the detent 71 and is, moreover, of sufficient length to extend out of that slot 15 and into a slot formed in an abutment 69^a (Figures 6, 7 and 9) in the auxiliary slide 69. Thus the spring 83 is made to bias or tend to force the plate member 79 always in clockwise direction, as viewed in Figures 6, 7 and 9. Clockwise movement of the plate 79 in clockwise direction is limited by an abutment 71^b (Figures 6 and 10) carried by the detent member 71. The functioning and purpose of the member 79 and related parts will be described in detail hereinafter.

The casing 60 is provided with suitable holes 84 for securing it to the door or the like and the casing is closed by a cover plate 85 (Figures 12 and 8) having suitable cutouts 86 to permit the securing screws that go through the holes 84 to by-pass and it is provided with opposed holes 87 (Figure 12) adapted to receive suitable screws threaded into lugs 88 (see Figure 6) formed upon the inside of the casing 60, thus to secure the closure plate 85 in place, the latter, moreover, coacting to prevent movement of various of the parts within the casing in a direction away from the outermost wall 60^c (Figure 10).

The cover plate 85 has rotatably mounted therein a bushing 89 provided with a transverse slot 90 to receive the operating bar 41 of a key-controlled mechanism such as the mechanism 42 of Figure 1 and already above described. At the inner end of the bushing 89 (Figures 8 and 12) the bushing has secured thereto a crank arm 91 carrying a projection 92, hereinafter termed a crank pin, whereby, when the key-controlled operating bar 41 is rotated and hence crank pin 92 is rotated, the above described bolt-operating mechanism may be operated, this time, however, from the outside of the door.

The crank pin 92, when it is appropriately rotated, is adapted to operate upon the detent 71 and coacting parts with results substantially identical to those resulting from a rotation of crank 72 (Figure 10) by the handle 74, all as is about to be described. The operating bar 41, however, extends well through the bushing 89 and into the casing 60 (see Figure 8), the detent member 71 (see now Figure 10) being cut out as at 71^c to permit the detent, as it moves to the right or left as viewed in Figures 6 and 7, to by-pass the end of the operating bar 41; moreover, the auxiliary slide 69 is also cut out or channeled as at 93 (Figures 6 and 7), the channel extending throughout a sufficient depth and length such that the inwardly projecting end of the operating bar 41 (Figure 8) is accommodated in the channel throughout the movement of the auxiliary slide 69 to the left as viewed in Figure 6 or to the right as viewed in Figure 7.

Various parts above described assume the position shown in Figure 6, when the bolts 61 and 62 are in withdrawn or retracted position, crank 72 assuming a dead center position (its axis being to the left of the screw 80 in Figure 6) and that

dead center relation securely holding the parts in retracted position. Moreover, the detent member 71 is, under the influence of spring 82, held in lowermost position, as viewed in Figure 6, from which it will be seen that its end (lower end in Figure 6) is in abutting relation but to the right of a lug or projection 60^c on the inside of the casing 60, this abutting relation blocking displacement of the bolts 61—62 and related parts in a direction to the left, as viewed in Figure 6. Moreover, spring 82 holds the parts 71 and the crank 72 in these positions.

Assuming now that the knob 74 is rotated to swing the crank 72 and hence the crank pin 75—80 (see now Figure 6) in counter-clockwise direction, the first movement of the crank pin 75—80 results in lifting the detent 79 out of abutting relation from the lug 60^c, detent 71 sliding upwardly in the ways or channels 70, further tensioning the spring 82.

Continued movement of the crank pin 80 effects conjoint movement of auxiliary slide 69 and main slide 64 in a direction toward the left, as viewed in Figure 6; member 79, of course, moving upwardly with the crank pin 75—80. Bolts 61—62 partake of a similar motion of translation, toward the left, but rotation of the bolts during this portion of the movement is precluded because of the arm 61^c (Figure 6) engaging and sliding along the lug 60^d within the casing 60, thus preventing relative movement between slides 69 and 64 inasmuch as relative movement between the helical slot 61^d in the bolt 61 and the cross-bar 67 cannot take place without rotational movement of the bolt 61.

As these movements are taking place, the innermost end of the operating bar 41 has the channel 93 (Figures 6 and 7) in the auxiliary slide 69 traversed relative to it, while the lever plate 79, still held by the spring 83 against the stop 71^b, as shown in Figure 6, is translated or moved in an arc over (as viewed in Figure 6) the operating bar 41.

As soon as the arm 61^c on the bolt 61 (Figure 6) comes to the left of the abutment or lug 60^d and substantially into the position shown in Figure 7, the bolt 61, projected from the casing and now projected into the keeper, may partake of rotation and such rotational movement thereupon takes place in that continued rotation of the crank 72 by knob 74 (Figure 10) or under the influence of the spring 82 causes the auxiliary slide 69 to continue to move toward the left and into the position shown in Figure 7, relative to the main slide 64 movement of which has ceased because now the arm 61^c on the bolt 61 (Figure 8) abuts against the left-hand wall of the casing 60. This relative movement causes the cross-bar 67 to move lengthwise of the bolts 61—62 and the latter are, through the cam or helical slots 61^d and 62^d, respectively rotated, thus bringing the T-shaped heads 61^a and 62^a thereof (Figure 7) crosswise of the openings in the keeper and thus definitely blocking withdrawal of the bolts from the keeper.

The crank pin 75—80 moves to a dead center position, this time to the left of the axis of the crank arm 72, being held in that position by the spring 82 and by the limiting action of the slot 77 in the auxiliary slide 69, slot 76 in the main slide 64 being suitably shaped to permit the above-described relative movement between the two slides to take place. Moreover, detent member 71 now becomes seated to the left of the abutment 60^c (see Figure 7) and in coaction with the

action of arm 61^c in being to the left of the abutment 60^d and in coaction with the dead center position of the crank pin 88, the detent 71 thus insures against forcing the now projected bolts in retrograde direction.

The latter portion of the above described movement of the crank pin 75—80 ultimately brings the lower edge 79^a (see Figure 7) of the pivoted plate member 79 into engagement with the operating bar 41 that projects into the channel 93 in the slide 69, and it is to be noted that the operating bar 41 precludes the member 79 from swinging in clockwise direction under the influence of its spring 83, all for a purpose to be about described.

The withdrawal of the bolts may take place under the control of the knob 14 by rotating the latter and hence the crank 72 in reverse direction, the above-described successive movements 20 and actions taking place but now in reverse order, plate member 79 always riding up over, as viewed in Figures 6 and 7, the operating bar 41.

Movement of the bolts from the retracted position of Figure 6 to the projected position of Figure 7 may, of course, also take place under the control of the operating bar 41 which, as above noted, actuates the crank arm 91 (Figures 8 and 12) and hence the crank pin 92. In that case, the crank pin 92 first strikes the portion 71^d (better shown in Figure 10) to start the upward (as viewed in the drawings) movement of the detent member 71, thereupon moving in between the upstanding flange 69^f and the abutment or upstanding portion 69^a (Figures 6 and 7) of the auxiliary slide 69, the parts 69^f and 69^a acting now virtually as a slot within which the crank pin 92 may function, a similar action taking place if the crank arm 91 is rotated in reverse direction to move the parts from the projected position of Figure 7 to the withdrawn position of Figure 6. In either case, the spring 82 acts to insure completion of the movements and to bring the crank 72 (Figure 10) into ultimate dead center position, and in either case, also, the lever plate 79 rides over (as viewed in the drawings) the operating bar 41.

If, however, assuming the bolts to be projected and in the position shown in Figure 7, the key-controlled mechanism, such as the mechanism 42 of Figure 1, by which the operating bar 41 of Figures 6—10 is rotated, is tampered with or withdrawn so as to withdraw the operating bar 41 with the intent of substituting for it a screw driver or other implement or tool, it is first to be noted that, as better shown in Figure 7, the withdrawal 55 of operating bar 41 amounts to withdrawing the member which stops further clockwise rotation of the lever plate 79 under the action of spring 83. With operating bar 41 therefore withdrawn, spring 83 snaps the plate-like member 79 into a position 60 relative to the auxiliary slide 69, as is shown in Figure 6, against a ledge 69^g (see now the enlarged sectional view of Figure 11) at the lower right-hand corner of the auxiliary slide 69.

Projecting from the ledge 69^g is a plunger 95 65 pressed upwardly by a spring 96, all housed in a recess 69^h in the ledge 69^g. The right-hand lower face of the lever arm 79 is provided with a recess 79^b (Figure 11) into which the plunger 95 is projected, thus properly alining the lower edge of the member relative to the remaining parts.

If, now, a screw driver is inserted through the slot 90 in the bushing 89 (Figures 8 and 12) and as is shown in Figure 9 where the screw driver S is projected through the slot in the bushing 89, 70 and the screw driver S rotated to swing the crank

arm 91 in clockwise direction, as viewed in Figure 9, the resultant initial and partial upward movement of the detent member 71, substantially into the position shown in Figure 9, now brings the edge surface 79^c of the lever plate 79 into contact with the screw driver or implement S, but this time at the under side thereof, as viewed in the drawings, and that action blocks further actuation of the mechanism in that direction, since the stop member or abutment 71^b on the detent member 71 prevents clockwise rotation of the lever member 79 beyond the position shown in Figure 9, it being now apparent that the member 79 cannot now by-pass the screw driver S or be carried up and over it. Thus, unauthorized 15 operation of the lock mechanism is precluded.

If, now, it is desired to restore the parts to normal, I need not take the lock mechanism apart or dismount it from the door or otherwise gain access to the interior thereof; I need merely operate the knob or handle 14 (the implement S of course now having been withdrawn) whereupon the parts may be restored to the withdrawn position and relation as shown in and above described in connection with Figure 6, thus bringing the member 79 (see Figure 6) to the right of the position which a new operating bar 41 (see Figure 6) is to occupy when a new bar and related key-controlled mechanism are associated with the outside portion of the door, whereupon the actions and operations above described may be repeated.

Turning now to Figures 13—18 inclusive, I have there shown a preferred form of certain features of lock mechanism, and referring first to Figures 13 and 14, I have provided a casing 100, in many respects similar to the casing 60 of Figures 6—12 whose left-hand end wall 100^a (Figures 13 and 14) is apertured as at 100^b and 100^c, these apertures being circular to provide bearings for the 40 slidable and rotatable bolts 101 and 102 but having lateral exposed extensions to receive the projections 101^a and 102^a (Figure 14) of the bolts 101 and 102, respectively, when the bolts are in the withdrawn position as shown in Figure 13. The 45 opposed projections 101^a and 102^a on the bolts 101 and 102 virtually give the bolts a T-shape, as was above described in connection with Figures 6 and 7, the keeper into which the bolts are projected being provided with holes shaped the same 50 as the holes or apertures 100^b and 100^c of the end wall 100^a (Figure 13) so that the left-hand bolt ends may enter into the keeper and through the holes in the end plate thereof, whereupon, when the bolts are rotated, the lateral projections 55 on the ends of the bolts take in back of the end wall of the keeper and thus prevent separation of the bolts from the keeper.

The right-hand ends of the bolts 101 and 102 are provided with shanks 103 and 104 (Figure 13) 60 that are cylindrical but of smaller diameter than the bolts 101 and 102, respectively, the shanks 103 and 104 terminating at their right-hand ends in heads 105 and 106, respectively. These heads 105 and 106 are substantially cylindrical and are 65 received in cylindrical recesses 107 and 108, respectively, in a slide block generally indicated at 109 and better shown in perspective in Figure 17.

The cylindrical recesses 107 and 108, which may be cast or drilled into the left-hand end 70 wall of the slide block 109, thus form bearings for the right-hand ends of the bolts 101 and 102, respectively, whereby these ends of the bolts are supported for rotation but it is to be noted that the bearing recesses 107—108 are of mate- 75

rially greater length than are the axial lengths of the cylindrical bearing heads 105-106 (Figure 13) so that relative movement between these heads (and hence the bolts) and the slide block 109 may take place, all for a purpose to be more clearly described hereinafter.

The bolts 101-102 (Figures 13 and 14) are provided with helical (sometimes erroneously called spiral) slots 101^b and 102^b, respectively, similar to the helical slots 61^d and 62^d above described in connection with Figure 6, the directions in which these helical slots extend relative to the respective axes of the two bolts being opposite to each other.

15 Into these slots 101^b-102^b extend the respective ends of a cross-head or cross-bar 110 (Figure 13) carried by an extension 111 directed forwardly (to the left in Figures 13 and 14) of the slide block 109 and preferably integrally formed therewith. This extension 111 with the cross-head or cross-bar 110 appears clearly in Figure 17.

The left-hand end 109^a of the slide block 109, being the end into which the cylindrical bearing recesses 107-108 are formed, is provided with dovetailed grooves 112-113 extending vertically (see Figure 17) and at the side ends of the otherwise plane end face of the end 109^a of the slide block 109. These dovetailed grooves 112-113 slidably receive and hold the correspondingly shaped vertical flanges 114-115 (see Figure 18) of a plate member 116, the parts being so shaped that the front face of the plate 116, as viewed in Figure 18, lies flush against the face of the end 109^a of the slide block. Moreover, the plate 116 (Figure 18) has a central slot 117 in which the extension 111 is accommodated when the plate 116 is slid down into place. As the latter movement takes place, slots 118 and 119 in the plate 116 (Figure 18) one on each side of the central slot 117, take over the shanks 103-104, respectively, of the bolts 101-102 (see Figure 13), and since the width of the slots 118-119 is less than the diameter of the heads 105-106 of the bolts, the bolts are thus held in assembled relation with 45 respect to the slide block 109 but, it is to be noted, in such a manner as to permit rotation of the bolts relative to the slide block 109 and also to permit relative sliding movement between the bolts and the slide block 109, the latter movement 50 being of a magnitude substantially equal to the length of the shanks 103-104 (see Figure 13). The dovetailed interfitting of the plate 116 with the slide block 109 is preferably one approaching a force-fit so that the relatively tight interfitting 55 holds the assembly plate 116 in place. Thus rapid assembly is made possible and also ease and rapidity of disassembly should repair or replacement be necessary.

60 The slide block 109 is slidably mounted in the casing 100, the longitudinal side walls of the latter being suitably shaped or formed to provide lengthwise extending and opposed ways 120 and 121 (see Figures 13, 14 and 15) and the sliding movement of the slide block 109 may be controlled by either of two cranks or crank elements, as is described in detail hereinafter.

One of these crank arms is the sheet metal arm 122 (Figures 14 and 15) suitably and rigidly secured to the inner end of the tubular shank 123 of the end knob 124 rotatably supported in the outer wall 100^b of the casing 100, this knob construction being not unlike the knob constructions 35-36 of Figure 1 and 73-74 of Figure 10, all being hollow. The end of the crank arm 122 75 has secured to it a crank pin or stud 125 (Fig-

ure 15) and is adapted to cooperate with certain parts related to the slide block 109 (Figure 17), being accommodated during its swinging movement in the transverse slot 126 in the slide block.

The slide block 109 (Figure 17) has a central longitudinal extending slot 127 ranging from its right-hand end toward the left-hand end, as viewed in Figure 17, thus virtually bifurcating the slide block 109. Extending transversely of the slide block 109 are ways 128 (Figure 17) in which 101 is guided for transverse sliding movement a member 129 having an elongated base portion 129^a which is interfitted with the undercut or dovetailed guideways 128 of the slide block 109 and an upstanding part or head 129^b (see Figures 19, 14 and 15). The transverse slot 126 (Figure 17) underlies the guideways 128 and thus underlies the transverse sliding member 129; however, crank pin or stud 125 (Figure 15) projects upwardly in the slot 126 (Figure 17) and to that 20 stud 125 the base portion 129^a of the member 129 is secured as by a screw 130, more clearly described hereinafter.

Slide block 109 (Figure 17 and also Figures 13 and 14) is cut out as at 131 in a downward direction but not throughout its entire depth or thickness, and in this cut out portion 131 there is mounted a stud 132 about which is coiled a spring 133 whose one end (see Figures 13 and 14) bears against the side face of the slide block 109 and whose other end bears against the head 129^b of the transverse sliding member 129; the spring 133 acting to force the member 129 in a downward direction, as viewed in Figures 13 and 14.

With this arrangement, and assuming that the bolts 101-102 are in withdrawn position (Figure 13) the crank 122 of the knob 124 (Figure 15) is in dead center position to the right of the axis 25^c of the tubular shank 123 of the knob, spring 133 30^c (Figure 13) insuring the maintenance of this position in that it acts upon the crank 122 through the slide member 129, the latter being secured to the crank pin or stud 125 by screw 130. In fact, 35^c the parts are so constructed that preferably, during this position, the stud or crank pin 125 bears against one of the side walls of the central longitudinal slot 127 (Figure 17) in the slide block 109.

If, however, the knob 124 is rotated to swing 500 the crank 122 in counter-clockwise direction, as viewed in Figure 13, the crank pin 125 starts to move upwardly against the action of spring 133, and into the transverse slot 126 (Figure 17) of the slide block 109, slide member 129 moving upwardly, as viewed in Figure 13, along the guideways 128, and as the crank swings in counter-clockwise direction, the slide block 109 starts to move in a direction toward the left, as viewed in Figure 13, imparting a similar motion of translation to the bolts 101-102, the latter being precluded from partaking of rotation during this stage of movement.

In this latter connection, it is to be noted that the bolt 101 is provided with a lug 101^e which 65^c bears against a ledge 134 extending lengthwise within the casing 100, the ledge 134 terminating short of the left-hand end wall 100^a of the casing 100 by a distance substantially equivalent to the width of the lug 101^e on the bolt 101. This 70^c lug 101^e, therefore, prevents rotation of bolt 101 until the latter has partaken of a motion of translation in a direction toward the left (Figure 13) until the lug 101^e comes to the point where it is 75^c ready to ride off of the ledge 134. By this time

the crank 122 has partaken of a rotation of approximately 90° in counter-clockwise direction from the position shown in Figure 13.

The other bolt 102 is prevented from rotation 5 by a somewhat analogous construction in that it is provided with a side lug 162^a (Figure 13) whose flat end face slides along one of the surfaces forming the guideway 121 for the slide block 109, that surface terminating, as at 135, 10 short of the end wall 100^a of the casing by a distance substantially equal to the width of the lug 192^c of the bolt 102. Here again bolt 102 partakes of movement of translation without rotation in a direction to the left throughout such 15 a distance as will bring the lug 162^a in the position where it is about to ride off of the guideway surface that terminates at 135, this taking place substantially simultaneously with the riding off of the ledge 134 of the lug 101^c of the 20 other bolt 101.

During this motion of translation, therefore, the force effecting such movement is transmitted to the bolts from the slide block 109 through the extension 111 and the oppositely projecting 25 arms 110 that engage into the helical cam slots 101^b and 102^b (Figure 13).

As soon as the bolts 101 and 102 are released for rotation by the riding off of the respective ledges of their respective lugs, these lugs, excepting for a slight end play or manufacturing tolerance, abut against the end wall 100^a of the casing 100 and now they act to prevent further motion of translation in a direction toward the left of the bolts 101—102, whereupon continued 30 counter-clockwise rotation of the crank arm 122 throughout approximately the next 90° of its rotation causes further movement toward the left of the slide block 109, thus causing the opposed arms 110 to move relative to the helical slots 101^b and 102^b, thereby causing rotation of the bolts, the latter having already entered the keeper by the time the motion of translation has ceased, the subsequent rotation turning the bolt heads 101^a and 102^a crosswise of the keeper 45 holes and thus preventing withdrawal of the bolts.

During this last stage of actuation of the bolts in the course of which they are rotated, the slide block 109 moves relative to the bolts 101—102; 50 this relative motion is made possible by reason of the depth of the cylindrical recesses 107—108 in the slide block 109 and within which recesses the bolt heads 105—106 are rotatably and slidably received.

The various parts above described and in their 55 final or "locked" position are shown in Figure 14, the last 90° range of movement of the crank having been aided by the spring 133 which insures that the crank pin or stud 125 is brought 60 into or beyond dead center position and hence held against that face of slot 127 (Figure 17) that is opposite the slot 126.

This dead center position aids in preventing 65 forced retrograde movement of the bolt or bolts, either rotational or of translation. Furthermore, the bolt lugs 101^c and 102^c, in having ridden off of the ledges 134 and 135 as above described, now are in virtual abutting relation to the left-hand ends, as viewed in Figure 14, of 70 these ledges, and thus aid in resisting any forcing of the bolt or bolts in retrograde or unlocking direction.

In withdrawing the bolt or bolts, the above 75 described cycle of operations is virtually reversed; the knob 124 and hence the crank 122

are rotated in clockwise direction, as viewed in Figure 14, and during about the first 90° of this movement, the bolt lugs 101^c and 102^c prevent the bolts from following the resultant movement in a direction toward the right of the slide block 109, thus causing the latter to move relative to the bolt or bolts, in an axial direction, and thus causing the bolts to be rotated in reverse direction, bringing the bolt lugs 101^c and 102^c out of their respective recesses and into position 100^a where they can slide along the ledges or faces which, as earlier described, were effective in preventing rotation. Having thus completed the reverse rotating of the bolts, the bolt heads 105—106 become engaged by the plate 116 at 15⁵ the left-hand end of the slide block 109 and which plate locks the bolt heads within the cylindrical recesses 107—108, whereupon movement throughout the next range of approximately 90° causes movement of translation of 20 the bolts in a direction toward the right until the position of the parts as shown in Figure 13 is reached, the crank again going to dead center and thus dependably holding the parts in withdrawn position. 25

The above described actuation of the mechanism may also be achieved by means of a suitable key-controlled mechanism, more particularly, a key mechanism like that of Fig. 1 and which, for purposes of convenience has been reproduced in Figure 15; thus, referring to Figure 15, the casing 100 with its above described bolt and bolt-operating mechanism is shown in Figure 15 as secured, as by appropriate screws passed through the screw holes 136 (Figure 14) 30 to the inside face of a door 24 in the hole 24^a of which is secured the key-controlled mechanism 42 adapted to receive, from the outside face of the door, a key 44 by means of which the operating bar 41 may be rotated of course 40 in response to the insertion into the key-controlled mechanism 42 of the proper key, mechanism 42 being secured in place by screws 43 and the back plate 42^b, as was described above in connection with Figure 1, the operating bar 41 45 passing through a suitable hole 42^a in the securing plate 42^b.

The casing 100 is closed by a closure plate 137 (Figures 15 and 16) which is provided with holes 138 (Figure 16) through which suitable screws 50 may be passed and threaded into the threaded holes 139 (Figure 14) provided in suitable shoulders or lugs upon the interior of the casing 10. Moreover, back or closure plate 137 is provided with suitable recesses 140 (Figure 16) to register 55 with the holes 136 (Figure 14) in the casing 100, thereby to permit the passage therethrough of the screws that secure the construction to the door 24 (Figure 15).

As is better shown in Figures 13 and 14, the 60 casing 100 is provided with suitably distributed shoulders or ledges 141 lying in the same plane and against which the closure plate 137 rests and against which it is held by the screws that pass through the holes 138 (Figure 16) in the plate 137 65 and that are threaded into the holes 139 (Figure 14) in the casing 100. Thus the closure plate 137 is held parallel to and spaced from the front wall 100^a (see Figure 15) of the casing 100, and takes part in holding the slide block 109 in assembled 70 relation to the guiding ways 120 and 121 (Figure 15) along which the slide block 109 slides. More specifically, the front end 109^a (Figure 17) of the slide block 109 is given such a vertical dimension that it snugly fits in between the ways 120—121 75

and the closure plate 137, along which the upper face of the front end 109^a of the block 109 (Figure 17) may glide. Also, the rear corner ends (Figure 17) of the slide block 109 are provided with up-standing lugs 142—143 which are similarly dimensioned to just about contact with the closure plate 137 as slide block 109 slides along the ways 120—121, thus coaxing to maintain slide block 109 in assembled relation to these guiding ways. The closure plate 137 has rotatably mounted in it a bushing 144 (Figure 16) provided with a rectangular slot 145 through which passes the operating bar 41 (Figure 15), bushing 44 being so positioned that its axis of rotation is coincident with the axis of the sleeve 123 and knob 124 (Figure 15); the latter parts being hollow, operating bar 41 (Figure 15) can and preferably does extend not only through the bushing 144 but also into the sleeve 123 of the knob 124, it being noted that the longitudinal slot 127 (see Figure 17) in the slide block 109 is of such extent longitudinally and transversely that the operating bar 41 is freely accommodated therein through the range of movement of the slide block 109.

Against the inside face of closure plate 137 and secured to rotate with the bushing 144 is a crank 146 (Figures 15 and 16) provided at its outer end with a stud or crank pin 147, crank 146 with its crank pin 147 being thus capable of being rotated by the key 44 (Figure 15) acting through the operating bar 41, crank pin 147 being available to actuate the above-described bolt-operating mechanism.

Crank pin 147 may accomplish an actuation of the bolts as was earlier above described in connection with the actuation of the bolts by the knob 124 (Figure 15) by the following arrangement:—Referring first to Figure 17, it will be recalled that there was above described the transverse ways 128 along which the member 129 is guided and that member 129 (Figures 13 and 14) is connected by screw 130 to the crank pin 125 (Figure 15) of the crank 122 operated by the knob 124. To this may be added the fact that the dovetailed guiding ways 128 (Figure 17) in the slide block 109 are formed in the bottom of a transverse slot 148 which extends to either side of the longitudinal slot 127, forming, to the right of the longitudinal slot 127, as viewed in Figure 17, two parallel spaced walls 149—150 between which the head 129^b (Figures 13, 14 and 15) of the member 129 moves as the member 129 is guided along the under-cut ways 128 by its base portion 129^a. Moreover, the walls 149—150 are curved or cut away as at 149^a and 150^a (Figure 17) so that, with the parts in the position shown in Figure 13, a counter-clockwise rotation of the key-controlled crank pin 147 (Figures 15 and 16) brings the crank pin just past the curved wall portion 150^a (Figure 17) and into engagement with the head 129^b (Figure 13), thereupon moving the slide member 129 against the action of spring 133 (Figure 13), at the same time, of course, actuating the knob-controlled crank pin 125 and crank 122 (Figure 15) which are connected to the slide member 129.

Key-controlled crank pin 147 moves upwardly, as viewed in Figure 13, into the slot 148 and between the walls 149—150 thereof (Figure 17) but at the same time a motion of translation in a direction toward the left (Figure 13) of the slide block 109 has taken place, crank 122 having been lifted out of its dead center position. This motion of translation, as above described

of the slide block 109 gives a similar motion to the bolts 101—102 until their parts 104^c and 102^c, respectively, ride off of the ledges 134—135, respectively, whereupon motion of translation of the bolts ceases while continued motion of translation of the slide block 109 rotates the bolts into the positions shown in Figure 14, key-controlled crank pin 147 riding out of the transverse slot 148 in the slide block 109, past the cut away wall portion 149^a (Figure 17), spring 133 (Figure 14) insuring that member 129 is moved to such a position that the crank pin 125 (Figure 15) of the crank 122 is again in dead center position. Thus, the bolts are thrown into the keeper and rotated, under the control of the key-controlled mechanism.

The key-controlled mechanism, if now actuated in reverse direction, puts the crank pin 147 (Figures 15 and 16) through a reverse or clockwise rotation as it would be viewed in Figure 14, whereupon the above-described steps are repeated but in reversed order, the mechanism finally being brought to the position of Figure 13 with the crank pin 125 of the crank 122 in its other dead center position.

Since the crank 146 (Figures 16 and 15) is on the inner inside face of the closure plate 137, slide block 109 (see now Figure 17) is cut out as at 151 so that, with the parts in the position shown in Figure 13, the crank 146 (Figure 16) is accommodated in this cut-out part 151.

Considering now, in connection with the structure of Figures 13—20, how I prevent operation of the bolt-operating mechanism by means of an implement inserted into the crank slot 145 (Figure 16) in place of the operating member 41, assuming that the intruder has been able to remove the key-controlled mechanism 142 (Figure 15) from the outside of the door 24, it is first to be noted, referring to Figure 13, that I provide a member 152 in the form of a plate-like arm (see also Figure 20) that rests upon the upper face of the base portion 129^a (see also Figure 19) of the transverse sliding member 129 and is pivotally related thereto by being held under the head of the screw 130 which, as above described, is suitably shouldered and is threaded into the crank pin 125 (Figure 15) whereby a free pivoting of the shank of the screw 130 relative to the slide member 129 and relative to this member 152 may readily take place. The holes for the shank of the screw 130 for members 129 and 152 are shown in Figures 19 and 20 at 129^c and 152^a. It will be understood, of course, that parts 152 and 129 may be related to crank pin 125 by a construction like that shown in Figure 10. Member 152 is thus made to move with the member 129, and the latter member, it will be recalled, is moved either by the knob-controlled crank pin 125 (Figure 15) or by the key-controlled crank pin 147 (Figure 15 and 16).

The head 129^b of member 129 is under-cut as indicated at 129^a in Figure 13 and as is better shown in Figure 19, to provide a housing for a spring 153 that encircles a pin 154 that passes through the head portion 129^b and through the under-cut or recessed part 129^a of the head in which the coiled part of the spring 153 is accommodated; one arm of spring 153 bears against the member 152 whose edge 152^b (Figure 20), with which the spring 153 contacts, is suitably slotted or grooved to maintain the spring 153 always in contact or engagement with the member 152. Spring 153 tends always to force the member 152

152 in clockwise direction, as viewed in Figure 13, and base portion 129^a (Figures 19 and 13) is provided with a shoulder 129^e against which member 152 is held by spring 153, particularly during 5 certain movements of the parts.

With the parts in the position shown in Figure 13, however, member 152 coacts with certain parts of the slide block 109. More specifically, referring 10 now to Figure 17, the lower corner portion of slide block 109 is shaped or cut out to provide a bottom portion 155 and an upper portion 156 spaced vertically from each other by substantially the thickness of member 152 (see Figure 20) so that spring 153, with the parts in the position shown in Figure 13, insures that member 152 rides into the space or slot between portions 155—156 (Figure 17). Now member 152 (Figure 20) is provided with an 15 upstanding abutment 157 which abuts against the right-hand edge of portion 156 (see Figures 17 20 and 13), being held in that relation by spring 153.

To insure an interlocking action between the member 152 and the slide block 109, the latter, turning now to Figure 17, is provided with a cylindrical bore 158 which extends into the lower portion 155, thus forming an exposed half-cylindrical recess 159. In the bore 158 and recess 159 is slidably received a cylindrical tumbler pin 160, better shown in Figures 15 and 13, being pressed upwardly, as viewed in these figures, by a spring 30 161 inserted into the bore 158 (Figure 17) and suitably held therein as by an end plug 162 (Figure 15). The under face of member 152 (see Figure 20) is shaped to have a half cylindrical recess 163 which, when member 152 is in the relation 35 to slide block 109 as shown in Figure 13, mates with the half cylindrical recess 159 (Figure 17) in the slide block 109, forming a complete cylindrical extension of the bore 158; and it is into this extension that the tumbler pin 160 (Figures 13 40 and 15) is projected by the spring 161, when this mating relation is achieved, tumbler pin 160 yielding against the action of spring 161 as the member 152 moves into the slot between the portions 155—156 (Figure 17) of the slide block 109.

45 The tumbler pin thus securely interlocks member 152 and slide block 109 against relative motion therebetween in the direction of the axis of the bolts 101—102 (Figure 13) all for a purpose hereinafter more clearly described.

50 The lower right-hand corner portion of slide block 109 (Figure 17) is also slotted to provide a bottom portion 164 and a portion 165 spaced upwardly therefrom, the slot therebetween being in alignment with the path of counter-clockwise 55 movement of member 152 (Figure 13) if and as member 152 is so swung.

Bearing in mind that the operating bar 41 (Figure 15) is of such length as to extend into the slot 127 (Figure 17) of the slide block 109 60 and assumes a position such as is shown in Figure 13 with the parts there shown, actuation of the bolts in the manners above described may freely take place and during such action the upward movement of member 129, as viewed in Figures 13 and 14, moves the member 152 bodily 65 in an upward direction, thus disengaging it from its interlocking relation to the slide block 109, spring 153 momentarily, at least, holding member 152 against the shoulder 129^e (Figures 13 and 19), the shoulder 129^e thus preventing the 70 spring 153 from swinging member 152 in clockwise direction beyond a position or a relative angle as shown in Figure 13. Slide member 129 and the safety member 152 thus move as a unit, retaining the angular relation therebetween as 75

shown in Figure 13, member 152 being accommodated, when necessary during its movement, in the slot between the portions 164—165 (Figure 17) of the slide block 109.

But member 152 continues to project, even 5 though moved upwardly with the slide member 129, across the longitudinal slot 127 (Figure 17) in the slide block 109, and as the latter moves to the left (as viewed in Figure 13) member 152 collides with the operating bar 41, being swung 10 upwardly in counter-clockwise direction thereby and being held in engagement with member 41 by spring 153. In a sense, member 152 rides over the operating bar 41 but the final locked position of the bolts brings about a relation of 15 member 152 to operating bar 41 as shown in Figure 14, the range of relative movement being insufficient to permit member 152 completely to ride over operating bar 41. Restoring the bolt-operating mechanism to bolt-withdrawn relation, brings about a reverse order of the above-described steps, member 152 swinging in clockwise direction over the operating bar 41 from the position shown in Figure 14 to the position shown in Figure 13, where it becomes again interlocked with the slide block 109. 20

If, however, considering the parts in the positions shown in Figure 14, the intruder has been successful in removing the key-controlled mechanism 42 (Figure 15) and has been able to withdraw the operating bar 41 from the bushing 144, such withdrawal of the operating bar 41 (see now Figure 14) removes the member 41 as an obstacle to the clockwise rotation of member 152 under the action of spring 153, whereupon 35 spring 153 immediately snaps member 152 in clockwise direction into the slot between the portions 156 and 155 of the slide member 109, thus immediately bringing about the interlocking relation between safety member 152 and slide block 40 109 as above described in detail, particularly in connection with the tumbler pin 160 (Figure 15).

If, now, the intruder inserts an instrument such as a screw driver into the bushing slot 145 (Figure 16) and attempts to rotate the bushing, member 152 no longer has the position shown in full lines in Figure 14, but has assumed the interlocked position shown in dotted lines in Figure 14, member 152 now being underneath or to the left of the implement (which assumes the position of the operating member 41 in Figure 14) instead of being above the inserted implement. 45

Resultant rotation through the implement of the crank 146 (Figures 15 and 16) proceeds only to such minor extent as is sufficient to bring the 55 slide block 109 in a direction toward the right, as viewed in Figure 14, where member 152, now in its downmost and interlocked relation to slide block 109, engages or contacts with the inserted implement, thus positively blocking the unlocking 60 or retrograde actuation of the bolts. Stated differently, such attempted actuation results physically in the attempt to cause member 152 to bypass the inserted implement (represented by the member 41 for present purposes, in Figure 14) 65 by endeavoring to cause it to under-ride the implement, something which it cannot do, rather than to over-ride it, something which it normally does with respect to the legitimate operating bar 41. 70

Moreover, such actuation tends to move the member 152 in clockwise direction from its dotted line position shown in Figure 14, but such actuation is positively precluded because of the abutting relation between part 157 (Figure 20) of 75

member 152 and part 156 (Figure 17) of the slide block 109, as well as by the positive interlocking achieved by the tumbler pin or plunger 160 (Figure 15). These parts positively preclude any yielding of member 152 in clockwise direction from its dotted line position shown in Figure 14.

This action is analogous and in some respects similar to that which takes place with the structure above described in connection with Figures 6-12 and, if reference is now made to Figure 9, the member 70 thereof, corresponding to the member 152 of Figures 13 and 14 will be seen to be in the above-described position, namely to the left of and underneath the inserted implement S, being positively interlocked with the detent member 71 (see now Figure 11) by the plunger or tumbler pin 95 which is projected by the spring 96 into the cylindrical recess formed by the mating half cylindrical recess 79^b and the upper part of recess 71^b. The dotted line position of member 152 in Figure 14 corresponds to the full line position of the safety member 79 of the construction shown in Figure 9, and broadly the safety actions, as will now be understood, are substantially similar.

Thus, intrusion is reliably precluded.

To restore the parts to normal, after such an attempted intrusion has been made, and as is desired when a new operating bar 41 and/or a new lock mechanism 42 (Figure 15) is desired to be installed, the knob 124 is simply rotated to move the parts from the position shown in Figure 14 to the position shown in Figure 13. The new key mechanism 42 and a new operating bar 41 are put in place, bar 41 extending well into the longitudinal slot 127 of the slide block 109 (Figure 17) and being capable, as above noted, even of being extended way into the hollow knob 124 and through the sleeve 123 of the latter. The relation of parts shown in Figure 13 is thus restored, member 152 finding itself to the right of operating bar 41, whence normal operation of the lock mechanism either through the knob 124 or the new key-controlled mechanism 42 may proceed in the manner above described in detail.

Various parts of the construction just described, such as the parts shown in Figures 17-20, for example, lend themselves readily to die-casting, thus facilitating manufacture.

It will thus be seen that there has been provided in this invention thoroughly practical and reliable means whereby unauthorized tampering with and manipulation of the bolt-operating mechanism is dependably precluded and that the arrangement lends itself to embodiment in thoroughly rugged and strong construction; moreover, it will be noted that these means lend themselves, as is typified in the several illustrative forms, readily to coaction with bolt actions and mechanisms of various kinds including, as herein illustrated by way of respective examples, a transverse bolt movement, as in the arrangement of Figures 1-5, a longitudinal bolt movement, as in the arrangements of Figures 6 and 13, and rotational bolt movements, as in the arrangements of Figures 7 and 14, and in so far as certain of the broader aspects of my invention are concerned, it is to be understood that I do not intend to limit myself, unless otherwise stated in the following claims, to any particular bolt action or movement or bolt-operating mechanism.

As many possible embodiments may be made of the above invention, and as many changes might be made in the embodiment above set

forth, it is to be understood that all matter hereinbefore set forth or shown in the accompanying drawings, is to be interpreted as illustrative and not in a limiting sense.

I claim:

1. In lock construction, in combination, a casing having a bolt and bolt-operating means therefor, means on one side of said casing for manually actuating said mechanism, means accessible from the other side of said casing adapted upon actuation to operate said mechanism, said last-mentioned means having an aperture for receiving therethrough the operating bar of a key-controlled means, a member moved by said mechanism extending into engagement with and on one side of an operating bar extending through said aperture and having a length sufficient to maintain contact with said operating bar throughout its range of movement, and spring means for holding said member in contact with said operating bar and acting, upon removal of said operating bar, to swing said member to the other side of the axis of said aperture, whereby, upon insertion of an implement or the like through said aperture, the implement blocks movement of said member and said member precludes actuation by said second-mentioned means of said mechanism.

2. A lock construction as in claim 1 provided with means whereby, after the operating bar or implement has been removed, the operation of the first-mentioned means restores said member to a position such that insertion through said aperture of an operating bar places said member on said first-mentioned side of the operating bar.

3. In lock construction, in combination, a casing having a bolt and bolt-operating means therefor, means on one side of said casing for manually actuating said mechanism, means accessible from the other side of said casing adapted upon actuation to operate said mechanism, said last-mentioned means having an aperture for receiving therethrough the operating bar of a key-controlled means, a member mounted for pivotal movement about an axis, spring means acting, during actuation of said mechanism, to swing said member about its pivot and to hold it in engagement with said operating bar and on one side thereof, whereby, upon removal of said operating bar out of said aperture, said spring means moves said member to the other side of the axis of said aperture and positions said member to move in a path, in response to subsequent attempted actuation of said mechanism by an implement projected through said aperture, to collide with said implement and block actuation of said mechanism.

4. In lock construction, in combination, a casing, a slide member slidably mounted within said casing, a bolt moved by said slide member, a key-controlled mechanism, means for moving said slide member in response to actuation of said mechanism, said means including a removable connecting element associated with said mechanism, a movably mounted member capable of assuming either of two positions, one of which is to one side of said connecting element, and means whereby movement of said slide member in bolt-retracting direction, when said movable member is on said side of said connecting element, abuts said movable member against said connecting element, thereby precluding bolt-retraction, said movable member being capable of being positioned to the other side of said connecting element, thereby to permit bolt-retraction.

5. In lock construction, in combination, a casing, a slide member slidably mounted within said casing, a bolt moved by said slide member, a key-controlled mechanism, means for moving said slide member in response to actuation of said mechanism, said means including a removable connecting element associated with said mechanism, a movable mounted member capable of assuming either of two positions, one of which is to one side of said connecting element, and means whereby movement of said slide member in bolt-retracting direction, when said movable member is on said side of said connecting element, abuts said movable member against said connecting element, thereby precluding bolt-retraction, and means normally holding said movable member on the other side of said connecting element, thereby to permit bolt-retraction, but acting, upon a removal of said connecting element, to position said movable member to be moved into said abutting relation upon replacement of said connecting element.

6. In lock construction, in combination, a bolt, key-controlled mechanism, mechanism for controlling the movement of said bolt in either locking or unlocking direction, said bolt mechanism including a connecting element related to said key-controlled mechanism, and means movable in response to actuation of said bolt mechanism but normally held in ineffective position by said connecting element and having a path of movement, when released upon removal of said connecting element, such that it collides with any member that may be substituted for said connecting element and prevents actuation of said bolt mechanism.

7. In lock construction, in combination, a bolt, key-controlled mechanism, mechanism for controlling the movement of said bolt in either locking or unlocking direction, said bolt mechanism including a connecting element related to said key-controlled mechanism, and means responsive to actuation of said bolt mechanism and normally held ineffective by said connecting element and capable of being released by the latter, upon removal of said connecting element, into a position such that said means, when said bolt mechanism is attempted to be operated by an implement substituted for said connecting element, will collide with said substituted implement and thereby precludes operation of said bolt mechanism.

8. In lock construction, in combination, a bolt, movable means for shifting said bolt into locking or unlocking position, an operating bar, means responsive to actuation of said operating bar for actuating said movable means, and means responsive to actuation of said movable means in bolt-unlocking direction and having a path of movement such that a member that may be substituted for said operating bar would lie therein, thereby to preclude further movement thereof and movement of said movable means in bolt-unlocking direction.

9. In lock construction, in combination, a casing, a movable bolt, a movable slide for controlling the position of said bolt and guided for transverse sliding movement by said casing, means including a member projecting into said casing for controlling the position of said slide member, a safety member pivoted in said casing and engaging said projecting member to one side of the latter, spring means holding said safety member on said side of said projecting

member and acting, upon removal of said projecting member, to move said safety member about its pivot to the other side of the axis of said projecting member, and a lost motion connection between said safety member and said slide member adapted upon actuation of said slide member in bolt-retracting direction to move said safety member, after the latter has been shifted in position by said spring upon a removal of said projecting member, against a member that may be substituted for said projecting member so as to stop movement of said slide member in bolt-retracting direction.

10. In lock construction, in combination, a casing, a movable bolt, a movable slide for controlling the position of said bolt and guided for transverse sliding movement by said casing, means including a member projecting into said casing for controlling the position of said slide member, a safety member pivoted in said casing and engaging said projecting member to one side of the latter, spring means holding said safety member on said side of said projecting member and acting, upon removal of said projecting member, to move said safety member about its pivot to the other side of the axis of said projecting member, and a lost motion connection between said safety member and said slide member adapted upon actuation of said slide member in bolt-retracting direction to move said safety member, after the latter has been shifted in position by said spring upon a removal of said projecting member, against a member that may be substituted for said projecting member so as to stop movement of said slide member in bolt-retracting direction, said lost motion connection having a sufficient range of lost motion to permit freedom of actuation of said slide member throughout its desired range while said safety member is held by said spring against said projecting member.

11. In lock construction, in combination, a casing, a movable bolt, a movable slide for controlling the position of said bolt and guided for transverse sliding movement by said casing, means including a member projecting into said casing for controlling the position of said slide member, a safety member pivoted in said casing and engaging said projecting member to one side of the latter, spring means holding said safety member on said side of said projecting member and acting, upon removal of said projecting member, to move said safety member about its pivot to the other side of the axis of said projecting member, and means transmitting motion from said slide member to said safety member in a direction to move the latter, after said spring has moved said safety member past the axis of said projecting member upon a removal thereof, into abutting relation to a member which may be substituted for said projecting member, thereby to preclude bolt-retracting movement of said slide member.

12. In lock construction, in combination, a casing, a movable bolt, a movable slide for controlling the position of said bolt and guided for transverse sliding movement by said casing, means including a member projecting into said casing for controlling the position of said slide member, a safety member pivoted in said casing and engaging said projecting member to one side of the latter, spring means holding said safety member on said side of said projecting member and acting, upon removal of said projecting member, to move said safety member about its

pivot to the other side of the axis of said projecting member, and means responsive to movement of said safety member to said other side of said axis for blocking movement of said slide member.

5 13. In lock construction, in combination, a casing, a movable bolt, a movable slide for controlling the position of said bolt and guided for transverse sliding movement by said casing, means including a member projecting into said 10 casing for controlling the position of said slide member, a safety member pivoted in said casing and engaging said projecting member to one side of the latter, spring means holding said safety member on said side of said projecting member 15 and acting, upon removal of said projecting member, to move said safety member about its pivot to the other side of the axis of said projecting member, means for latching said safety member upon the conclusion of its said movement in response to said spring, and means whereby said latched safety member precludes movement of said slide member.

14. In lock construction, in combination, a casing, a movable bolt, a movable slide for controlling the position of said bolt and guided for transverse sliding movement by said casing, means including a member projecting into said casing for controlling the position of said slide member, a safety member pivoted in said casing and engaging said projecting member to one side of the latter, spring means holding said safety member on said side of said projecting member and acting, upon removal of said projecting member, to move said safety member about its pivot to the other side of the axis of said projecting member, means for latching said safety member upon the conclusion of its said movement in response to said spring, and an abutment against which said slide member rests when in one position, said safety member having means positioned, when in latched position, to engage at least part of said slide member to hold it against said abutment.

15. In lock construction, in combination, a bolt, key mechanism, mechanism for controlling the movement of said bolt in either locking or unlocking direction, said bolt mechanism including a connecting element related to said key mechanism, means movable in response to actuation of said bolt mechanism but normally held in ineffective position by said connecting element and having a path of movement, when released upon removal of said connecting element, such that it collides with any member that may be substituted for said connecting element so as to prevent actuation of said bolt mechanism, and additional means for operating said bolt mechanism and acting through the latter to restore said movable means.

16. In lock construction, in combination, a casing having front and back walls each having rotatably mounted therein a crank, a bolt, a member slidably transversely of said casing and guided thereby for actuating said bolt, said slideable member having two spaced parts between which either of said cranks, upon rotation thereof, may engage for controlling the movement of said slideable member, said two spaced parts being spaced in a direction transversely of said casing, a spring-opposed head slidably carried by said slideable member for movement lengthwise of said casing and between said two spaced parts and normally projected outwardly therefrom, said head being positioned in the path of travel of either of said cranks upon rotation thereof, and abutment means carried by at least one of said walls of said casing and coacting with said head when projected to hold said slideable member against movement, said abutment means being dimensioned so that said head, when moved inwardly between said parts by either of said cranks bypasses said abutment means and thereby permits movement of said slideable member by a crank.

said walls of said casing and coacting with said head when projected to hold said slideable member against movement, said abutment means being dimensioned so that said head, when moved inwardly between said parts by either of said cranks bypasses said abutment means and thereby permits movement of said slideable member by a crank. 5

17. In lock construction, in combination, a casing having front and back walls each having rotatably mounted therein a crank, a bolt, a member slidably transversely of said casing and guided thereby for actuating said bolt, said slideable member having two spaced parts between which either of said cranks, upon rotation thereof, may engage for controlling the movement of said slideable member, said two spaced parts being spaced in a direction transversely of said casing, a spring-opposed head slidably carried by said slideable member for movement lengthwise of said casing and between said two spaced parts and normally projected outwardly therefrom, said head being positioned in the path of travel of either of said cranks upon rotation thereof, and a single abutment on a wall of said casing coacting with said head, said abutment being dimensioned in the direction of movement of said head such that the head disengages said abutment upon being pressed inwardly between said parts by a crank, whereupon sliding movement of said slide may take place, and being dimensioned in the direction of sliding movement of said slideable member such that the head engages to one side of said abutment when said slideable member is at one extreme of its movement and engages at the other side of said abutment when said slideable member is at the other extreme. 30

18. In lock construction, in combination, a casing having front and back walls each having rotatably mounted therein a crank, a bolt, a member slidably transversely of said casing and guided thereby for actuating said bolt, said slideable member having two spaced parts between which either of said cranks, upon rotation thereof, may engage for controlling the movement of said slideable member, said two spaced parts being spaced in a direction transversely of said casing, a spring-opposed head slidably carried by said slideable member for movement lengthwise of said casing and between said two spaced parts and normally projected outwardly therefrom, said head being positioned in the path of travel of either of said cranks upon rotation thereof, said slideable member having a bore extending lengthwise of said spaced parts and exposed in the space between the latter and said head having a shank slidably received in said bore, the spring opposing said head being housed in said bore and acting against said shank, and abutment means carried by at least one of said walls of said casing and coacting with said head when projected to hold said slideable member against movement, said abutment means being dimensioned so that said head, when moved inwardly between said parts by either of said cranks bypasses said abutment means and thereby permits movement of said slideable member by a crank. 45

19. In lock construction, in combination, a casing having a bolt, slideable means guided with- 70 in said casing for actuating said bolt, said casing having abutment means adjacent the path of movement of said slideable means, a member slidably mounted upon said slideable means for movement transversely of the latter and adapted to 75

coact with said abutment means to limit the movement of said slidable means, an apertured member movably carried by said casing for actuating said slidable means, a member projected through the aperture in said apertured member for actuating the latter, and movable means responsive to movement of said slidable means normally engaging said projected member and held by the latter in ineffective position, and spring means for moving said movable means to the other side of said projected member upon removal of the latter out of its aperture, whereby movement of said movable means in response to attempted actuation of said slidable means in response to operation of a member inserted into said aperture in place of said projected member is stopped by said inserted member and movement of said slidable means thereby precluded.

20. In lock construction, in combination, a casing having a bolt, slidable means guided within said casing for actuating said bolt, said casing having abutment means adjacent the path of movement of said slidable means, a member slidably mounted upon said slidable means for movement transversely of the latter and adapted to coact with said abutment means to limit the movement of said slidable means, an apertured member movably carried by said casing for actuating said slidable means, a member projected through the aperture in said apertured member for actuating the latter, a safety member pivotally carried by said slidable member and having means for holding it against said projected member when said slidable means is in bolt-projected position, said holding means acting, upon a withdrawal of said projected member to swing said safety member past the position occupied by said projected member prior to the withdrawal of the latter, thereby positioning said safety member to be moved into collision with a device which may be inserted through said aperture in place of said withdrawn projected member, thereby to cause said device to block withdrawal-actuation of said bolt.

45. 21. In lock construction, in combination, a casing having a bolt, slidable means guided within said casing for actuating said bolt, said casing having abutment means adjacent the path of movement of said slidable means, a member slidably mounted upon said slidable means for movement transversely of the latter and adapted to coact with said abutment means to limit the movement of said slidable means, a crank arm pivotally carried by said casing adapted upon rotation to coact with said slidable member to disengage it from said abutment means and move said slidable means and thereby actuate the bolt, said crank arm having an aperture at its axis for receiving an operating member for rotating the 60 crank arm, said slidable member being moved by said crank from one side of the axis thereof to the other, means pivotally carried by said slidable member and movable therewith from one side of said axis to the other, said pivotal means 65 having a spring for holding it in engagement with said operating member when said slidable means and bolt are in bolt-projected position, whereby upon removal of said operating member, said pivotal member is moved into a position to prevent movement of said slidable member toward the other side of said axis.

70. 22. In lock construction, in combination, a casing having a projectable and rotatable bolt, said bolt having a shank with a round head at its inner end, slidable means guided within said cas-

ing for movement in the direction of projection of said bolt, said slidable means having bearing means for rotatably and slidably supporting and peripherally engaging said round head at the inner end of the shank of said bolt and having means engaging the shank between the bolt and the head, whereby relative motion of translation between said bolt and said slidable means may take place, means for moving said slidable means in bolt-projecting direction, means preventing 10 rotation of said bolt during a portion of said movement of said slidable means, and means effective during the remaining portion of said movement of said slidable means for rotating said bolt.

15. 23. In lock construction, in combination, a casing having a projectable and rotatable bolt, said bolt having a shank with a round head at its inner end, slidable means guided within said casing for movement in the direction of projection of said bolt, said slidable means having bearing means for rotatably and slidably supporting and peripherally engaging said round head at the inner end of the shank of said bolt and having means engaging the shank between the bolt and the head, whereby relative motion of translation between said bolt and said slidable means may take place, means for moving said slidable means, and means operative to effect relative motion of translation between said bolt and said slidable 30 means to take place only after a certain movement of said slidable means in bolt-projecting direction has taken place.

24. In lock construction, in combination, a casing having a projectable and rotatable bolt, said bolt having a shank with a round head at its inner end, slidable means guided within said casing for movement in the direction of projection of said bolt, said slidable means having bearing means for rotatably and slidably supporting and peripherally engaging said round head at the inner end of the shank of said bolt and having means engaging the shank between the bolt and the head, whereby relative motion of translation between said bolt and said slidable means may take place, means controlled from the exterior of said casing for moving said slidable means, a connection between said slidable means and said bolt for effecting rotation of said bolt upon relative movement of translation between said bolt and said slidable means, and means for controlling the point in the movement of said slidable means at which said relative motion of translation is to take place.

25. In lock construction, in combination, a casing having a projectable and rotatable bolt, said bolt having an inner end provided with a shank and a head, a slide block within said casing, said slide block having a recess within which said bolt head is rotatably received, means for moving said slide block and for effecting rotation of said bolt, a retaining plate member for locking said head within said recess, and means for holding said plate member to said block comprising an interfitting dovetail and groove.

65. 26. In lock construction, in combination, a casing having a projectable and rotatable bolt, said bolt having an inner end provided with a shank and a head, a slide block within said casing, said slide block having a recess of greater 70 depth than the length of said head and within which recess said bolt head is slidably and rotatably received, means for moving said slide block and for effecting rotation of said bolt, a retaining member for locking said head in said recess and 75

thereby determining the extent of slidable movement between said bolt and said slide block, and means detachably interengaging said plate member and said slide block.

5 27. In lock construction, in combination, a casing having a projectable and rotatable bolt, said bolt having an inner end provided with a shank and a head, a slide block within said casing, said slide block having a recess within which said bolt head is rotatably received, said recess being of an axial dimension greater than the axial dimension of said head, whereby relative axial movement between said block and said bolt may take place, means responsive to relative axial movement 10 therebetween for effecting rotation of said bolt, and means for determining the point in the path of movement of said slide block at which said relative axial movement is to take place.

15 28. In lock construction, in combination, a casing having a projectable and rotatable bolt, said bolt having an inner end provided with a shank and a head, a slide block within said casing, said slide block having a recess within which said bolt head is rotatably received, said recess being of an axial dimension greater than the axial dimension of said head, whereby relative axial movement between said block and said bolt may take place, means attached to said slide block adjacent the open end of said recess for preventing said 20 head from emerging from said recess, thereby to determine the extent of said relative axial movement, means responsive to relative axial movement therebetween for effecting rotation of said bolt, and means for determining the point in the 25 path of movement of said slide block at which said relative axial movement is to take place.

30 29. In lock construction, in combination, a casing having a projectable and rotatable bolt, said bolt having an inner end provided with a shank and a head, a slide block within said casing, said slide block having a recess within which said bolt head is rotatably received, said recess being of an axial dimension greater than the axial dimension of said head, whereby relative axial movement between said block and said bolt may take place, a member carried by said slide block adjacent the open end of said recess for preventing said head from coming out of the latter, thereby to determine the extent of said relative axial movement, said member and said block having portions shaped to interfit, means responsive to relative axial movement therebetween for effecting rotation of said bolt, and means for determining the point in the path of movement of said slide block 35 at which said relative axial movement is to take place.

35 30. In lock construction, in combination, a bolt, movable means for shifting said bolt into locking or unlocking position, an operating bar, means responsive to actuation of said operating bar for actuating said movable means, and a movable safety member for physically engaging and blocking movement of said movable means, whereby movement of said bolt is precluded, said safety member being normally held ineffective by said operating bar.

40 31. In lock construction, in combination, a bolt, movable means for shifting said bolt into locking or unlocking position, an operating bar, means responsive to actuation of said operating bar for actuating said movable means, a safety member movable into or out of engagement with said movable means, latch means for holding said safety member in engaged position with said movable 45 means, and means positioned in the path of move-

ment of said safety member after the latter has interengaged said movable means for blocking movement of said movable means.

5 32. In lock construction, in combination, a bolt, movable means for shifting said bolt into locking or unlocking position, an operating bar, means responsive to actuation of said operating bar for actuating said movable means, a safety member movable into or out of engagement with said movable means, latch means for holding said safety member in engaged position with said movable means, and means whereby said operating bar normally holds said safety member out of engagement with said movable means.

10 33. In lock construction, in combination, a bolt, movable means for shifting said bolt into locking or unlocking position, an operating bar, means responsive to actuation of said operating bar for actuating said movable means, a safety member movable into or out of engagement with said movable means, said safety member being positioned, when in engaged relation to said movable means, to have a path of movement in response to attempted actuation of said movable means by a part that may be substituted for said operating 15 bar such that it will collide with said part, and means whereby the removal of said operating bar for purpose of substituting therefor said part is effective to move said safety member into said engaged relation.

20 34. In lock construction, in combination, a bolt, movable means for shifting said bolt into locking or unlocking position, an operating bar, means responsive to actuation of said operating bar for actuating said movable means, a safety member 25 movable into or out of engagement with said movable means, said safety member being positioned, when in engaged relation to said movable means, to have a path of movement in response to attempted actuation of said movable means by a part that may be substituted for said operating 30 bar such that it will collide with said part, said operating bar, when said movable means has been shifted into bolt-locking position, holding said safety member out of said engaged position.

35 35. In lock construction, in combination, a bolt, movable means for shifting said bolt into locking or unlocking position, an operating bar, means responsive to actuation of said operating bar for actuating said movable means, a safety member 40 movable into or out of engagement with said movable means, said safety member being positioned, when in engaged relation to said movable means, to have a path of movement in response to attempted actuation of said movable means by a part that may be substituted for said operating 45 bar such that it will collide with said part, said operating bar, when said movable means has been shifted into bolt-locking position, holding said safety member out of said engaged position.

45 36. In lock construction, in combination, a casing member having an opening, a bolt projectable through said opening, a movable slide member for controlling the position of said bolt, means including an operating bar projecting into said casing member for controlling the position of said slide member, a safety device pivotally 50 carried by one of said members and normally engaging said operating bar to one side of the latter, and spring means holding said safety device on said side of said operating bar and acting, upon removal of said operating bar, to move 55

said safety device about its pivot to the other side of the axis of said operating bar.

37. A lock construction as in claim 36, provided with latch means operating, when said spring moves said safety device about its pivot, to hold said safety device in its new position.

38. A lock construction as in claim 36, provided with a releasable latch means for releasably holding said safety device in the position into which 10 it is moved by the spring means.

39. In lock construction, in combination, a casing member having an opening, a bolt projectable through said opening, a movable slide member for controlling the position of said bolt, means 15 including an operating bar projecting into said casing member for controlling the position of said slide member, a safety device movably carried by one of said members and normally engaging said operating bar on that side of the latter remote 20 from said slide member, said safety device having a range of movement and being dimensioned so that it remains engaged on the said side of said projecting bar throughout the range of movement 25 of said movable slide member, and means effective, upon removal of said operating bar, to move said safety device to the other side of the axis of the operating bar and thereby positioning said device to prevent attempted actuation 30 of said slide member by a part that may be substituted for the operating bar by colliding with such substituted part.

40. In lock construction, in combination, a casing member having an opening, a bolt projectable through said opening, a movable slide member for controlling the position of said bolt, means 35 including an operating bar projecting into said casing member for controlling the position of said slide member, a tumbler member movably carried by said slide member, there being means co-acting with said tumbler member and said slide member to move the latter in response to turning movement of said operating bar, a safety member movably carried by said tumbler member 40 and normally engaging said operating bar to one side of the latter, and means whereby said safety member, after said slide member has been moved into bolt-projecting position, is moved, upon removal of said operating bar, to the other 45 side of the axis of the operating bar and is thereby positioned to collide, in response to attempted actuation of said slide member in bolt-withdrawing direction by a part that may be substituted for said operating bar, with said substituted part.

41. A lock construction as in claim 40 in which the casing member has means operable from the other side of said casing member and has mechanism inside of said casing member responsive to actuation of said operable means for controlling 50 the slide member and also for actuating said tumbler member, whereby said safety member, upon removal of the operating bar or the part substituted therefor, may be restored to its normal position and the operating bar inserted.

42. A lock construction as in claim 40 in which there are means pivotally supporting the safety member with respect to said tumbler member, whereby said safety member is movably carried by said tumbler member, and in which the means 55 for moving the safety member, upon removal of the operating bar, comprises a spring.

43. A lock construction as in claim 40 in which the slide member is provided with means for confining the movement of the tumbler to a direction 60 transversely of the slide member, the casing

member being provided with a crank rotatably mounted in a wall thereof opposite that through which the operating bar projects, the axes of the latter and of the crank being coincident, the arm of the crank being pivotally connected to said 5 tumbler member and thereby causing the latter and said safety member carried thereby to move in an arc the center of which is the said coincident axes.

44. A lock construction as in claim 40 in which 10 the slide member is provided with means for confining the movement of the tumbler member in a direction transversely of the slide member, the casing member being provided with a crank rotatably mounted in a wall thereof opposite that 15 through which the operating bar projects, the axes of the latter and of the crank being substantially coincident, and the arm of the crank being pivotally connected to said tumbler member and thereby causing the latter and said safety member carried thereby to move in an arc the center of which is the said substantially coincident axes, and in which there are means pivotally supporting the safety member with respect 20 to said tumbler member, whereby said safety member is movably carried by said tumbler member and in which the safety member is of a length greater than the radius of the arc of movement 25 of the tumbler member so that it cannot move into colliding position so long as said operating bar is not withdrawn.

45. A lock construction as in claim 1 in which there is means pivotally supporting the member that engages the operating bar relative to the 35 casing and means forming a lost motion connection between said member and the bolt-operating means.

46. A lock construction as in claim 1 in which there is means pivotally supporting the member 40 that engages the operating bar supported by the casing and has a portion extending toward said bolt-operating means, the latter being provided with two spaced parts, the space between which is greater than the dimension of said portion, between which said portion extends, thereby forming a lost motion connection between said member and said bolt-operating means.

47. A lock construction as in claim 1 in which the means accessible from the other side of said 50 casing for operating the bolt mechanism includes a crank with a crank pin, the said member that extends into engagement with the operating bar having means relating it to said crank to partake of a movement commensurate with that of 55 the crank pin.

48. A lock construction as in claim 1 in which the means accessible from the other side of the casing is a crank and in which the member that extends into engagement with the operating bar 60 is provided with means for pivotally connecting the member and the crank, whereby the member partakes of movement in an arcuate path in response to actuation of the crank.

49. A lock construction as in claim 1 in which 65 the means accessible from the other side of the casing is a crank, a tumbler slidably carried by said bolt-operating means, means forming a connection between the crank and said tumbler whereby the latter, in response to actuation of 70 the crank, slides relative to the bolt-operating means, and means whereby the member that engages the operating bar partakes of a movement commensurate with that of said tumbler.

50. In lock construction, in combination, a cas- 75

ing having two projectable and rotatable bolts, said bolts having inner ends provided with a shank and a head, a bifurcated slide block within said casing, the bifurcation being formed by a 5 slot extending in the direction of sliding of said block, said block having two recesses open at the front end of the latter and transversely spaced, each recess receiving the shank and head of one of said bolts, means engageable with the heads 10 on said shanks for preventing disconnection of said bolts from said block while permitting relative sliding and rotating movement, said slide block having a transverse slideway crossing said slot, a member slidably related to said slideway, and means for moving said slide block and for 15 effecting rotation of said bolts said means including a crank member carried by said casing and adapted upon rotation to move said member along its slideway and to shift the slide block 20 and an operating bar substantially coaxial with the axis of said crank member and which may project into said slot in the block, the transverse sliding movement of said member in said slideway being of sufficient range to move said member 25 away from said slot whereby said member may by-pass said operating bar.

51. A lock construction as in claim 50 in which the slideable member in the slideway carries a safety member extending into engagement with 30 and on one side of the operating bar and dimensioned to maintain contact with said operating bar throughout the range of movement of said safety member as determined by the movement of said slideable member and of said block, and 35 means biasing said safety member in a direction to maintain said contact and to cause said safety member, upon removal of said operating bar, to swing to the other side of the axis of the operating bar.

52. A lock construction as in claim 50 in which the slideable member carries a safety member movable with respect thereto, the slide block having an abutment or stop with which said safety member may engage, and means whereby 45 the safety member is held out of engagement with said abutment or stop but is moved into engagement therewith upon removal of said operating bar.

53. A lock construction as in claim 50 in which the slide block is provided with another slot underneath a portion of the slideway and in which the casing is provided with, and pivotally carries, another crank member, said crank member having a crank pin that projects through said 55 last-mentioned slot and is in pivotal engagement with said slideable member.

54. A lock construction as in claim 50 in which the casing is provided with another crank member that has a crank pin, the crank pin being in 60 pivotal engagement with said slideable member, a safety member pivoted coaxially with said crank pin and normally extending into engagement with and on one side of said operating bar and having a length sufficient to maintain contact with 65 said operating bar throughout the range of movement of said crank pin so long as said operating bar is not removed, and means biasing said safety member in a direction to maintain said contact with said operating bar throughout said range of movement.

55. In lock construction, in combination, a casing having two projectable and rotatable bolts, said bolts having inner ends provided with a shank and a head, a bifurcated slide block with- 70 in said casing, the bifurcation being formed by a

slot extending in the direction of sliding of said block, said block having two recesses open at the front end of the latter and transversely spaced, each recess receiving the shank and head of one of said bolts, means sufficiently closing said recesses to prevent the heads of said shanks from coming out of their respective recesses, thereby permitting said bolts to rotate and slide relative to said block, two substantially coaxial crank members supported respectively in opposed walls 10 of said casing and having connections with said slide block to slide the latter relative to the casing, one of said crank members being apertured to receive a connecting bar that may extend into said slot in said slide block, and means operative 15 during a first portion of sliding movement of said block to project said bolts from said casing and during a second portion of sliding movement thereof to rotate said bolts.

56. In lock construction, in combination, a 20 casing having two projectable and rotatable bolts, said bolts having inner ends provided with a shank and a head, a bifurcated slide block within said casing, the bifurcation being formed by a slot extending in the direction of sliding of 25 said block, said block having two recesses open at the front end of the latter and transversely spaced, each recess receiving the shank and head of one of said bolts, means sufficiently closing said recesses to prevent the heads of said shanks 30 from coming out of their respective recesses, thereby permitting said bolts to rotate and slide relative to said block, two substantially coaxial crank members supported respectively in opposed walls of said casing and having connections with 35 said slide block to slide the latter relative to the casing, one of said crank members being apertured to receive a connecting bar that may extend into said slot in said slide block, coacting cam and follower means respectively on said bolts 40 and said slide block for effecting rotation of said bolts, and means whereby said cam and follower means become effective only during relative sliding movement between said bolts and said slide block.

57. In lock construction, in combination, a casing having two projectable and rotatable bolts, said bolts having inner ends provided with a shank and a head, a bifurcated slide block within said casing, the bifurcation being formed by a 50 slot extending in the direction of sliding of said block, said block having two recesses open at the front end of the latter and transversely spaced, each recess receiving the shank and head of one of said bolts, means sufficiently closing said recesses to prevent the heads of said shanks from 55 coming out of their respective recesses, thereby permitting said bolts to rotate and slide relative to said block, two substantially coaxial crank members supported respectively in opposed walls of said casing and having connections with said slide block to slide the latter relative to the casing, one of said crank members being apertured to receive a connecting bar that may extend into said slot in said slide block, means operative 60 during a first sliding movement of said block to prevent relative sliding movement between said bolts and said block and to prevent rotation of said bolts, thereby to project the latter out of the casing, and means operative during a second 65 portion of sliding movement of said block to permit relative sliding movement between said bolts and said block to take place and to effect rotation of said bolts.

58. In lock construction, in combination, a 75

casing having a wall in which is rotatably mounted a crank, said crank being apertured at its axis and having an operating bar received through the aperture therein, movable bolt means within said casing and positionable in either locking or unlocking position and having means for coaction with said crank, whereby operation of said crank moves said movable bolt

means into locking or unlocking position, and a safety device within said casing movably related to said movable bolt means and adapted to coact to block movement of said movable bolt means but being normally engaged by said operating bar 5 and thereby held ineffective.

ADAM SCHOOREL.
